UNITED STATES PATENT OFFICE.

GEORGE W. URMSON, OF JERSEY CITY, NEW JERSEY.

DOOR-HANGER.

1,180,624.

Specification of Letters Patent. Patented Apr. 25, 1916.

Application filed September 8, 1915. Serial No. 49,551.

To all whom it may concern:

Be it known that I, GEORGE W. URMSON, a subject of the King of Great Britain, residing at Jersey City, in the county of Hudson and State of New Jersey, have invented 5 certain new and useful Improvements in Door-Hangers, of which the following is a full, clear, and exact specification.

This invention relates to door hangers 10 and especially to guides and supports for the bottom corners of folding doors.

The object of devices of this kind is to support the door as it is opened and closed, and at the same time guide the door along a 15 slotted plate inserted in the floor.

One object of the present invention is to provide the guiding means with means for automatically keeping the groove in the floor plate clear of dust and other foreign 20 matter which is apt to collect therein and interfere with the ready opening and closing of folding doors thus equipped.

Another object is to provide means for adjusting the supporting and combined 25 guiding and slot cleaning devices vertically on the folding doors to allow for uneven places in the floor.

Other objects will appear as the description proceeds.

30 The invention will be first hereinafter described in connection with the accompanying drawings, which constitute part of this specification, and then more specifically defined in the claims at the end of the description.

35 In the accompanying drawings, wherein similar reference characters are used to designate corresponding parts throughout the several views: Figure 1 is a side elevation 40 of the bottom corner of a folding door equipped with a device constructed substantially in accordance with my present invention, part of one of the side plates being broken away to disclose the frame on which 45 the caster and guide are adjustably mounted. Fig. 2 is an edge view with the marginal portion of the door broken away. Fig. 3 is a section on the line III—III of Fig. 2. Fig. 4 is a detached vertical section 50 of the adjusting member, and Fig. 5 is a plan view of the same.

Referring more particularly to the drawings, 1 designates a folding door and 2 the two side plates which 55 close a space 3 in the bottom edge portion of the door in which the caster and guide are

housed. The side plates 2 have bolts 4 for securing them to the door, and on their inner faces said plates are provided with ribs or ledges 5 between which a frame 6 is held 60 against vertical movement. One of the bolts 4 is passed through the frame 6, as clearly illustrated in Figs. 1 and 2, for securing the same against lateral movement along the side plates. 65

The frame 6 has an opening 7 extending horizontally therethrough and in which the upper end portion of an adjusting member 8 is arranged. Said adjusting member 8 has a milled or nut-shaped upper end 10, a 70 screw-threaded lower end 11 and a reduced intermediate portion 9, the diameter of the latter portion being less than the screw-threaded lower end 11, so that it can follow 75 said screw-threaded portion into a corresponding screw-threaded passage in the bottom of the frame 6 for adjusting the caster and guide vertically with respect to the frame and door as may be required.

The caster and guide are carried by casting 13 from which a pin or spindle 12 extends up through the adjusting member 8 and the top of the frame 6, the top of the casting 13 resting against the bottom of the adjusting member and the pin or pintle 12 85 being adapted to freely turn in said member and the frame to permit the guide to follow the groove in the floor plate as the folding door is rolled open and closed. The guide 14 is plow-shaped and fits the groove 90 15 in the floor plate 16. The caster 17 is mounted preferably at one side of the plow-shaped guide on an axle pin 18 and rests upon the top surface of the floor plate for supporting the door. 95

One side of the frame 6 is provided with a slot 19 and one of the plates 2, namely the one next to that side of the frame, has a slot 20 registering therewith for permitting a suitable instrument to be inserted into engagement with the milled or nut-shaped head 10 of the adjusting member for rotating the same to effect a vertical adjustment of the casting 13, as will be readily understood. A locking screw 21 is introduced 100 through the other side plate and adjacent side of the frame 6 to engage and hold the head 10 of the adjusting member when it has been placed at the desired adjustment. 105

It will be noted that the guide 14 is plow-shaped at both ends and that these plow-shaped parts are beveled in opposite direc- 110

tions so that the dust and dirt will be thrown out of the grooves or slot 15 in the floor plate at the same side of said groove, when a folding door is moved in either direction, 5 making it much easier to sweep up this dirt without getting it back into the groove or slot.

The plow-shaped guide will always keep the groove in the floor plate clear, so that 10 accumulated material will not interfere with the proper operation of folding doors. Heretofore, when sawdust or other dust proof materials have been used when sweeping, and the floors have been provided with 15 grooved plates for folding doors, the sawdust or other materials becoming packed into a solid mass in the grooves of the plates, have greatly interfered with the proper operation of the folding doors.

20 Having thus described my invention, what I claim as new and desire to secure Letters Patent of the United States is:—

1. The combination with a slotted floor 25 plate, of a guide for folding doors, said guide fitting the slot in the floor plate and having a beveled plow-shaped edge for automatically removing accumulated dirt from said groove as the guide is moved along the same in opening and closing the door.

2. The combination with a slotted floor 30 plate, of a guide for folding doors, said guide fitting the slot in the floor plate and having beveled plow-shaped edges at both ends for

automatically removing accumulated dirt from said groove as the guide is moved along 35 the same in opening and closing the door, the two plow-shaped ends of the guide being beveled in opposite directions for the purpose specified.

3. The combination with a caster having 40 a pintle, of an inclosure for the caster, a frame having a screw-threaded passage, an adjusting member having a screw-threaded portion fitting in the screw-threaded passage in the frame and around the pintle, 45 said member also having a head for rotating the same, there being an opening in the inclosure opposite said head permitting the insertion of an instrument for turning the same, and means for locking the head in ad- 50 justed position.

4. The combination with a caster having a pintle, of a pair of facing supporting plates having horizontal ledges on their inner faces, a frame fitted between said 55 plates and retained against vertical movement by said ledges, said frame having a screw-threaded passage, and an adjusting member having a screw-threaded portion 60 extending into the screw-threaded passage in the frame and fitted loosely around the pintle.

In testimony whereof I have signed my name to this specification.

GEORGE W. URMSON.
